Primary Examiner — Susan Bennett Hattan*Assistant Examiner* — Marie Fast Horse(74) *Attorney, Agent, or Firm* — Brinks Gilson & Lione(57) **CLAIM**

I claim the ornamental design for a telephone base unit, as shown and described.

DESCRIPTION

FIG. 1 is a diametric perspective view of a telephone base unit of the present invention;

FIG. 2 is a rear and top perspective view thereof;

FIG. 3 is a front view thereof;

FIG. 4 is a rear view thereof;

FIG. 5 is a first side view thereof;

FIG. 6 is a second side view thereof;

FIG. 7 is a top view thereof; and,

FIG. 8 is a bottom view thereof.

The broken lines shown represent portions of the telephone base unit that form no part of the claimed design. In addition, the dot-dash lines shown in FIGS. 1-8 define the bounds of the claimed design.
